UNITED STATES PATENT OFFICE.

DAVID HANSEN, OF RAYMOND, WASHINGTON.

COMBINATION IRONING AND CLOTHES CHEST.

Application filed March 16, 1921. Serial No. 452,867.

To all whom it may concern:

Be it known that I, DAVID HANSEN, a citizen of the United States, residing at Raymond, in the county of Pacific and State of Washington, have invented certain new and useful Improvements in Combination Ironing and Clothes Chests, of which the following is a specification.

This invention relates to combination articles of furniture, and the primary object of the invention is to provide a combined ironing and clothes chest, which when in its folded or collapsed position may be used as an ordinary table if so desired, the device being so constructed as to present a pleasing and novel appearance to the eye.

A further object of the invention is to provide an improved ironing table embodying a cover and arranged to normally house the ironing boards, and the clothes basket for receiving the ironed clothes and for overlying the upper surface of the work top of the table.

A further object of the invention is to provide a novel means for arranging the ironing boards on the work top, so that the same can be conveniently interfitted to permit of folding of the cover thereover.

A further object of the invention is to provide an improved combined clothes chest and ironing board comprising a body having a plurality of doors or compartments therein for receiving the soiled or ironed clothes, a work top, a pivoted cover for overlying the work top, a pair of ironing boards carried by the work top and adapted to be enclosed by the cover, and a collapsible tray or basket for supporting the clothes after or during the ironing process.

A still further object of the invention is to provide a novel means for attaching the boards to the work top so as to permit the boards to be swung at any angle, and so as to prevent the tipping of the boards during the ironing process.

A still further object of the invention is to provide an improved combined clothes chest and ironing table of the above character, which is durable and efficient in use, one that is simple and easy to manufacture, and one which can be placed upon the market at a reasonable cost.

With these and other objects in view, the invention consists in the novel construction, arrangement and formation of parts, as will

be hereinafter more specifically described, claimed and illustrated in the accompanying drawings, forming a part of this specification, in which drawings:

Figure 1 is a perspective view of the improved combined ironing and clothes chest, the various parts of the chest being shown in their open or extended positions.

Figure 2 is a vertical longitudinal section through the improved chest showing the parts thereof in their folded or collapsed position, and

Figure 3 is an end elevation of the improved ironing or clothes chest showing the cover in section, and in a raised position, and the clothes tray or basket in its open extended position, parts of the tray also being shown in section, the cover also being shown in dotted lines in its normal or closed position.

Referring to the drawings in detail, wherein similar reference characters designate corresponding parts throughout the several views, the letter A indicates the improved combined ironing and clothes chest, and as shown consists of the corner legs or standards 5 to which may be secured the end panels 6, and the rear or back longitudinally extending panel 7. It is also to be understood that the legs are to be connected by suitable transverse braces 8 and longitudinally extending braces 9, which may form a part of the end and rear panels. The front part of the chest is adapted to be closed by doors 10 and 11, and these doors may be provided with suitable hand holds 12. A lower wall 13 is provided and an upper wall or work top 14. This top may be suitably braced against springing or bending by means of a suitable beam or support 15. On the upper surface of the work top 14 and adjacent to the opposite ends thereof are arranged the ironing boards 16 and 17. The ironing board 16 can be of the usual or any desired length and it is preferred that the same be formed relatively wider and longer than the board 17, which can be conveniently used for ironing sleeves and the like. Thus it can be seen that in the improved device two different sized ironing boards have been provided. The ironing board 16 as stated, is arranged adjacent to one end of the work top 14 and extends toward the opposite end of the work top and ends short thereof, while the relatively small ironing board 17 is se-

cured adjacent to the other end of the work top 14 and extends inwardly toward the opposite end thereof. These ironing boards each include work tops 18 and 19 respectively, which may be shaped in any preferred manner or of the usual ironing board type. Secured to the lower surface of each one of the work boards 18 and 19 are the relatively large heavy supporting blocks 20 and 21 respectively, and these blocks form means for forming a solid support for the ironing boards so as to prevent the tilting thereof. Each of the boards 16 and 17 are held in position by means of bolts 22 and 23 respectively. The bolts 22 and 23 form pivots on which the boards are adapted to rotate, so that the boards 16 and 17 can extend at any angle from the work top which may be desired. As clearly shown in Figure 2 of the drawings, the ends of the bolts are countersunk so as to not interfere with the working surface of the work boards 18 and 19 of the ironing boards 16 and 17.

A cover 25 is provided for the ironing boards, and this cover includes a top 26 and depending transverse ledges 27 and longitudinal front and rear ledges 28. The front ledge 28 may be provided with suitable handles 29. The top 26 and the ledges 27 and 28 form a complete housing for the ironing boards and at the same time gives an ornamental appearance to the chest as a whole, and a casual observation of the chest does not give the impression that the same is for work, such as ironing and the like. In order to form a support for the clothes being ironed or to form a rest for the clothes directly after they have been ironed, a tray 30 is provided. This tray 30 consists of longitudinally extending slats 31, which are held in spaced relation by spacer blocks 32. Transverse cleats 33 are also provided for holding the slats in their correct position. As clearly shown in Figures 1 and 3 of the drawings the tray 30 is pivotally connected at its inner edge to the rear longitudinally extending ledge 28 by means of suitable hinges 34. In order to hold the tray in an angular position during the ironing process, flexible supporting cables or ropes 35 are provided. These ropes or flexible supports 35 have their upper ends knotted, as at 36 and secured in suitable blocks 37 secured to the inner surface of the top 26 of the cover 25. The flexible supports or ropes 35 are knotted as at 38 intermediate their ends, which form the means for supporting the tray in its angular position, and it can be seen that the tray 30 is adapted to assume an angle of substantially 45° in relation to the work top 14. The lower end of the ropes or supporting members 35 may be secured to the work top 14.

The board 17 is much lower than the board 16, and this board is adapted to swing

under the board 16 when the same are in their collapsed or inoperative positions. This forms a means whereby both of the same can be readily housed by the cover 25. The tray 30 is also adapted to be swung in close parallel relation to the pocket 26 when in its folded position as clearly shown in Figure 2 of the drawings.

In use of the improved cabinet, it can be seen that the lower portion thereof is particularly adapted to receive clothes either before or after being ironed, and when the cover 25 is in its closed position it also can be used as a table. When it is desired to iron the clothes, it is merely necessary to raise the cover to the position shown in Figure 3 of the drawings, and the tray 30 will automatically assume the position as shown in Figure 3 or if the tray sticks the same may be pulled out to this position. The clothes can then be placed upon the work top 14, and the boards 16 and 17 are moved to any desired angle which may be best suited to the person who is ironing the clothes, and the clothes are laid on the board in the ordinary manner. After the clothes have been ironed the same may be placed on the tray 30 where they can be afterward removed.

As shown a removable shelf 7' is provided for the lower portion of the chest carried upon suitable cleats 8' provided for that purpose.

The chest forms an exceptionally simple and convenient means for handling clothes and is an added convenience to the household.

Changes in details may be made without departing from the spirit or scope of this invention; but,

I claim:

1. A clothes chest including a work top, a cover for housing the work top, and a hinged tray carried by the top and adapted to extend at an angle to the work top when in its operative extended position.

2. A combined ironing and clothes cabinet comprising a chest including a work top having compartments therein arranged below the work top, a cover carried by the work top arranged to overlie the same, a tray hingedly secured at its inner longitudinal edge to the work top, and flexible guys secured to the cover of the work top and the tray for holding the same at an angle to the work top and cover.

3. A combined clothes and ironing chest having a work top, a cover for overlying the work top, the cover including a top board and depending ledges, a tray hingedly secured at its inner longitudinal edge to the inner surface of the cover, and flexible guys connecting the outer end of the tray to the cover and table top.

4. In an ironing cabinet, a work top, a

cover carried by the work top arranged to normally overlie the same including a top board and a skirt, a clothes tray hingedly connected with the cover at its inner longitudinal edge, flexible guys connecting the cover and work top for holding the cover in a raised position in relation to the work top, guides formed on the tray for receiving the guys, and means formed on the guys for 5 limiting the downward movement of the tray whereby the same will be held at an angle to the work top and cover when the 10

cover is in its raised position in relation to the work top.

5. In an ironing cabinet, a work top, a 15 cover for overlying the work top, ironing boards carried by the work top, a clothes tray hingedly carried by the cover, the cover including a top board, and a depending skirt, the skirt being adapted to house said 20 clothes tray and the ironing boards when the same is in its lowered position.

DAVID HANSEN.
